			128/DIG. 12

FIG. 1 is an upper front perspective view of the bag pump;
 FIG. 2 is an upper rear perspective view of the bag pump;
 FIG. 3 is a lower front perspective view of the bag pump;
 FIG. 4 is a front view of the bag pump;
 FIG. 5 is a rear view of the bag pump;
 FIG. 6 is a left side view of the bag pump;
 FIG. 7 is a right side view of the bag pump;
 FIG. 8 is a top view of the bag pump; and,
 FIG. 9 is a bottom view of the bag pump.
 The broken lines shown in the drawings illustrate portions of
 the bag pump that form no part of the claimed design.
